(57) **CLAIM**

The ornamental design for a foldable bicycle lock, as shown and described.

DESCRIPTION

FIG. 1 is a perspective view of a foldable bicycle lock, showing my new design;

FIG. 2 is a front view thereof;

FIG. 3 is a rear view thereof;

FIG. 4 is a top side view thereof;

FIG. 5 is a bottom side view thereof;

FIG. 6 is a left view thereof; and,

FIG. 7 is a right view thereof.

The nature and intended use of the article in which the design is embodied is that of a foldable bicycle lock.
